UNITED STATES PATENT OFFICE.

WILLIAM B. SHAW, OF NEW YORK, N. Y.

DESIGN FOR A FOOT FOR FOOTSTOOLS.

SPECIFICATION forming part of Design No. 29,792, dated December 13, 1898.

Application filed November 17, 1898. Serial No. 696,728. Term of patent 7 years.

To all whom it may concern:

Be it known that I, WILLIAM B. SHAW, a citizen of the United States, residing at the city of New York, borough of Brooklyn, in the county of Kings and State of New York, have invented and produced a new and original Design for a Foot for Footstools, of which the following is a specification, reference being had to the accompanying drawing, forming a part thereof, in which is represented a perspective view of a foot for footstools embodying the features of my design.

The design consists of diverging body members combined at their converging ends to

form a foot member, the foot member being 15 at an angle to the lower portions of the body members. The upper ends of the body members are bent in an opposite direction to the foot member and are provided with oppositely-extending arms. 20

I claim—

The design for a foot for footstools, herein shown and described.

WILLIAM B. SHAW.
